UNITED STATES PATENT OFFICE.

WILLIAM H. DINSPERL, OF NEW YORK, N. Y., ASSIGNOR TO ATLAS DEVICES COMPANY, INC., A CORPORATION OF NEW YORK.

CARRIER CHECK FOR PNEUMATIC-DISPATCH-TUBE SYSTEMS.

Application filed October 11, 1921. Serial No. 507,094.

To all whom it may concern:

Be it known that I, WILLIAM H. DINSPERL, a citizen of the United States, residing at New York city, in the county of New York, State of New York, have invented certain new and useful Improvements in Carrier Checks for Pneumatic-Dispatch-Tube Systems; and I do hereby declare the following to be a full, clear, and exact description of the invention, such as will enable others skilled in the art to which it appertains to make and use the same.

This invention relates to a check or detent for carriers in a pneumatic dispatch tube system and involves the provision of a device which is employed in connection with a sending tube, and installed either at the mouth of the tube or at an intermediate point, to check or prevent any considerable reverse travel of the carrier after once being dispatched; also to grip the carrier upon its insertion into the tube and hold it in the mouth of the tube against falling out under the action of gravity until the vacuum in the line is sufficiently developed to force the carrier to take flight.

A complete unit tube line in a pneumatic dispatch tube system usually consists of a sending tube for dispatching carriers from a central tube room to an outlaying station, a return tube from the latter station back to the tube room which is connected by means of a suction tube with a vacuum drum, and a by-pass at the outlying station connecting the sending and return tubes. In order that carriers may be dispatched from the outlying station to the tube room, the return tube is provided with an opening into which carriers may be inserted, and this opening, or intermediate opening as it is termed, is closed by means of a door or flap. Since the return tube is connected to the suction or vacuum drum and the sending tube has connection with the latter through the by-pass and return tube, it will be evident that when the intermediate door at the outlying station is opened to dispatch a carrier to the tube room, the line is short-circuited, i. e., the suction through the line extends from the drum through the return tube to the intermediate opening and no further, and thus the sending tube is cut out of the vacuum line or rendered dead during the interval of time that the door remains open. Now if the opening of the door occurs after the dispatch

of a carrier in the sending tube and the carrier happens to be in a vertical or upwardly extending length of the tube, the latter being cut from communication with the suction drum is without sufficient pressure either to 60 propel the carrier forward or to sustain it at the particular point of its travel, with the result that the carrier falls back until it strikes a sharp bend or a horizontal or nearly horizontal stretch of tubing. In practice 65 this condition is frequently encountered and the reverse travel of the carrier oftentimes amounts to a drop of one or two floors before the sending tube is again put into communication with the suction drum by the 70 closing of the intermediate door. Obviously this back travel or drop of the carriers results in a loss of power for, when the sending tube is again connected, the carrier must be propelled back to the point from which it 75 dropped.

One of the objects of this invention is to provide a check or detent for installation at any intermediate point along a tube line which will operate to prevent backward 80 travel of the carrier under the conditions above described.

In some of the more recent types of pneumatic dispatch tube systems, the sending tubes are concentrated at one point in the 85 tube room so that their terminal openings or bell mouths are within easy reach of an operator for the dispatch of carriers to outlying stations. These tubes, as a rule, extend upwardly at a steep inclination, oftentimes 90 approaching the vertical. When the system is of the open type, i. e., one in which the bell mouths of the sending tubes are always open, and is equipped with control devices or regulators operating to produce and 95 maintain a vacuum in the line only when a carrier is inserted and is in transit in the line, or in any type of system where the sending tube is temporarily cut off and rendered dead by the opening of an intermediate 100 door, the operator must in inserting a carrier in the bell-mouth of a sending tube hold it until the vacuum rises to a point where the unbalanced pressure of the atmosphere forces the carrier to take flight. This 105 condition would exist in any case where the carriers would fall from the mouths of the sending tubes under the action of gravity unless held, irrespective of the arrangement or disposition of these tubes, and so the dis- 110

patch of carriers is consequently slow and inconvenient.

The invention, therefore, further aims to facilitate the dispatch of carriers by providing a check which will grip a carrier upon its insertion into a sending tube and hold it against falling out under the action of gravity until the carrier is forced by the vacuum in the line to take flight.

10 The check includes a stop which is adapted to project into the transit tube and is constructed and arranged to permit forward movement of the carrier as it is inserted into the tube, or during its flight, but which is operable upon reverse movement of the carrier to engage the carrier and prevent continuance of its reverse or backward movement passed the check.

20 The construction of the carrier is such as to provide means, usually consisting of projecting surfaces or ledges formed by end buffer heads, for engagement by the check upon reverse or backward movement of the carrier and the check, which is preferably in the form of a ball check actuated by gravity, is arranged normally to restrict the cross sectional area of the tube sufficiently to insure an effective blocking or checking of the carrier against its reverse movement passed the check.

25 In one form of construction in which a ball check is employed, the tube has an opening and a chamber is provided adjacent the opening in which the ball is movable to project through the opening. The outer wall of the chamber is preferably formed to provide a chamber of varying depth relative to the tube whereby the ball, loosely confined therein, may be moved to project through or be withdrawn from the opening. Thus the outer wall of the chamber may be formed to provide a receptacle for the ball, the latter normally taking a position in the shallow portion of the chamber under the action of gravity in which position it projects through the opening or slot in the tube and effectively prevents reverse movement of the carrier passed its position in the tube, and the carrier has means, usually provided by its end buffer heads, to engage the ball upon forward movement of the carrier in the tube to force the ball into the receptacle where it is withdrawn from the path of the carrier.

30 55 The invention is illustrated in the accompanying drawings in application, as an example, to an upwardly extending sending tube such as is employed in dispatching carriers from a central station to various outlying stations, in which,

Fig. 1 illustrates the carrier check applied to the mouth of a sending tube;

Fig. 2 is a view along the line 2—2 of Fig. 1;

60 65 Fig. 3 is a view showing the check ap-

plied to a vertical rise of tubing as between floors;

Fig. 4 is a sectional view of the check and stretch of tubing illustrated in Fig. 3; and

70 Fig. 5 is a view along the line 5—5 of Fig. 3.

The check as applied to the mouth of a sending tube will first be described.

Referring to Figs. 1 and 2, as indicated 75 the sending tube 1 is inclined at an angle to the horizontal, the rise or inclination of these tubes being customarily quite abrupt and often approaching the vertical. The far end of the tube at the out station has 80 connection through a by-pass, the return tube and suction tube with exhaust means usually a vacuum drum, which construction is not illustrated but will be readily understood by those conversant with the art. 85 The end of the sending tube 1 is provided with an opening or slot 2 and carries the fitting 3 terminating in a bell mouth 7. The fitting 3 has a chamber or receptacle 4 formed therein for confining a relatively 90 heavy ball 5 which is preferably made of solid metal. The chamber 4 surrounds the opening 2 in the sending tube, and its outer wall 6 is shaped so that the chamber is of decreasing depth toward its lower end as indicated at 4^a. Near the outer end of the chamber the wall 6 is bulged outwardly to provide a cavity or receptacle for receiving the ball 5 as indicated at 4^b. The 95 inclination of the sending tube 1, and accordingly also the fitting 3 and its chamber 4, is such that the ball 5 under the action of gravity normally occupies a position at the lower end of the chamber where a portion of the ball projects through the opening 2 100 into the sending tube near the mouth 7.

105 The carrier 8 which is shown partly inserted in the sending tube 1 is a type of carrier provided with end buffer heads 9 projecting outwardly from the shell or body of 110 the carrier 10 thus providing ledges or projecting surfaces 11 near the ends of the carrier. When the carrier is inserted in the tube 1, the ball 5 normally being at the lower end of the chamber 4 and projecting into the 115 tube through opening 2 is engaged by one of the buffer heads 9, the outer edges of the buffer heads 9 being beveled as at 12 to present surfaces for engaging the ball when the carrier is inserted in the tube. As the carrier is moved forwardly into the tube the ball 5, engaged by one of the surfaces 12, is pushed ahead of the carrier until it lodges in the cavity or depression 4^b in which position no part of the ball projects through the 120 opening 2 into the tube and the buffer head of the carrier is free to pass forwardly or upwardly to the position indicated in the drawing. When the carrier has been inserted in the tube a sufficient distance to per-

mit the ball to pass between the inner edge of the outer surface of the buffer head and the wall ^{4a}, the ball drops to the lower part of the chamber ⁴ under the action of gravity and again projects through the opening ², thus restricting the size of the opening and blocking the passage of the buffer head in the reverse direction. The carrier will remain in this position until the vacuum in the tube forces the carrier to take flight in the tube. It will be evident that if the carrier is inserted sufficiently far the same action will take place between the ball and the buffer head at the opposite end of the carrier in which case the carrier will be entirely within the sending tube with the surface ¹² of the lowermost buffer head in contact with the ball ⁵ until the carrier takes flight.

In order that the fitting ³ may be readily and securely fastened on the end of the sending tube ¹, the fitting is split as at ¹³ between a pair of lugs ¹⁴ provided with bolt holes through which a bolt ¹⁵ passes, and the fitting is provided with a slot ¹⁶ through which the ball ⁵ may be moved by inserting a finger in the event of its sticking or otherwise failing to operate properly.

Referring to Figs. 3, 4 and 5, the check is shown applied to an intermediate point in the sending tube. In this form a section of tubing ¹⁷ is cut out of the main transit tube ¹ to which the fitting ³ provided with flanges ¹⁸ is secured by rivets ¹⁹ adjacent the opening or slot ² with which the section of tubing is provided. This tube section is secured between the ends of the main transit tube ¹ by means of sleeves ¹⁹. By moving these sleeves upwardly or downwardly along the transit tube ¹, the tube section ¹⁷ may readily be adjusted in place or removed for repairs. The operation of the check at the intermediate point in the line as illustrated will be readily understood from the description of the operation as given in connection with the check applied to the mouth of the sending tube. It will be evident that the forward movement of the carrier through the tube after being dispatched will be unobstructed past the check, the buffer heads of the carrier engaging the ball and forcing it into the cavity or receptacle ^{4b} in which position it will be held by the buffer heads. The normal position of the ball ⁵, however, is that in the lowermost end ^{4a} of the chamber ⁴ in assuming which, under the action of gravity, the ball will gradually project through the opening or slot ² and block the reverse movement of the carrier passed the position of the check as when an intermediate door in the line is opened.

I claim:

1. In a pneumatic despatch tube system having an upwardly extending sending tube, a carrier check comprising a gravity actuated stop situated at a point in the tube, and

means on the carrier adapted to be engaged by the stop, said stop being held by gravity in a position to normally restrict the cross-sectional area of the tube, and which is constructed and arranged to permit forward movement of the carrier through the tube, and operable upon reverse movement of the carrier toward the sending end of the tube to engage said means on the carrier and prevent continuance of the reverse movement of the latter, under the action of gravity beyond said point.

2. In a pneumatic despatch tube system having an upwardly extending sending tube, a ball check, situated at a point in the tube, which is constructed and arranged to permit forward movement of the carrier through the tube, and which is operable upon reverse movement of the carrier toward the sending end of the tube to engage the carrier and prevent continuance of its reverse movement under the action of gravity beyond said point.

3. In a pneumatic despatch tube system having an upwardly extending sending tube, a ball check situated at a point in the tube, which is constructed and arranged to permit forward movement of the carrier through the tube, and which is operable by action of gravity to engage the carrier upon its reverse movement toward the sending end of the tube, to prevent continuance of the reverse movement beyond said point.

4. In a pneumatic despatch tube system having an upwardly extending sending tube, and wherein the carrier is provided with projections at its ends, a ball check for the carrier which is constructed and arranged to permit the insertion of the carrier and its forward movement into the tube, and operable upon release of the carrier to engage said projections on the carrier and prevent the dropping out of the latter from the mouth of the tube.

5. In a pneumatic despatch tube system having an upwardly extending sending tube and wherein a carrier is provided with buffer heads at its ends, a ball check for the carrier, which is constructed and arranged to permit the insertion of the carrier and its forward movement into the tube, and which is operable upon release of the carrier to engage one of said buffer heads on the carrier and prevent the dropping out of the latter from the mouth of the tube.

6. In a pneumatic despatch tube system having a sending tube provided with an opening, a check for the carrier including a chamber adjacent said opening and a ball in said chamber movable therein to project through said opening.

7. In a pneumatic despatch tube system having a sending tube provided with an opening, a check for the carrier including a chamber adjacent said opening and having

an outer wall, and a ball in the chamber, said outer wall being formed to provide a varying depth of the chamber relative to the tube, and said ball being movable in the chamber to project through and to be withdrawn from said opening.

8. In a pneumatic despatch tube system having a sending tube provided with an opening, a check for the carrier including a chamber having an outer wall, and a ball loosely confined in the chamber and normally projecting through the opening in the tube said outer wall being formed to provide a receptacle for receiving the ball wherein the latter is withdrawn from said opening.

9. In a pneumatic despatch tube system having an upwardly extending sending tube provided with an opening, a check for the carrier including a chamber having an outer wall, and a ball loosely confined in the chamber and normally projecting through the opening in the tube for engaging and preventing reverse movement of the carrier toward the sending end of the tube beyond the check, said outer wall being formed to provide a receptacle for receiving the ball wherein the latter falls by gravity and is withdrawn from said opening, and means on the carrier for engaging the ball and moving it into said receptacle as the carrier moves forwardly through the tube past said check.

10. In a pneumatic despatch tube system having an upwardly extending sending tube

provided with an opening near the mouth thereof, a check for the carrier comprising a chamber adjacent the mouth of the tube and having an outer wall, a ball in said chamber, and buffer heads on the ends of the carrier and projecting outwardly from the body portion thereof, said ball being loosely confined in the chamber and normally projecting through the opening in the tube to engage a buffer head of the carrier to prevent the latter from dropping out of the tube, and said outer wall of the chamber being formed to provide a receptacle for receiving the ball wherein the latter falls by gravity and is withdrawn from said opening and into which it is forced by a buffer head when the carrier is inserted in the tube.

11. In a pneumatic despatch tube system having a sending tube provided with an opening, a check for the carrier including a chamber adjacent said opening and a gravity-actuated body freely movable in said chamber to project through said opening, substantially as described.

12. In a pneumatic despatch tube system having a sending tube provided with an opening, a check for the carrier including a chamber adjacent said opening and a gravity-actuated, spherical body freely movable in said chamber to project through said opening, substantially as described.

In testimony whereof I affix my signature.

WILLIAM H. DINSPERL
